FIG. 2.

UNITED STATES PATENT OFFICE.

CHARLES EMILE PELLETIER, OF NEW ORLEANS, LOUISIANA.

REMOTE-CONTROL ELECTRIC SWITCH.

1,254,534.

Specification of Letters Patent. Patented Jan. 22, 1918.

Application filed February 2, 1915, Serial No. 5,653. Renewed October 2, 1917. Serial No. 194,416.

To all whom it may concern:

Be it known that I, CHARLES EMILE PELLETIER, a citizen of the Republic of France, and a resident of New Orleans, in the parish of Orleans and State of Louisiana, have invented a new and Improved Remote-Control Electric Switch, of which the following is a full, clear, and exact description.

This invention relates to a remote control switch for electric circuits whereby the switch can be opened or controlled from a point more or less remote.

The invention has for its general objects to improve and simplify the construction and operation of electric switches of the character referred to so as to be reliable and efficient in use, comparatively inexpensive to manufacture and keep in repair, and so designed that it is capable of either automatic or manual operation, chattering is avoided, and positive closing secured.

A further object of the invention is the provision of a switch having one or a plurality of sets of contacts corresponding with the phases or lines in which the movable contact or contacts are thrown into and out of open or closed circuit position by a solenoid having separate windings and independently energized from the service mains or other source, the circuits of the windings being opened and closed by electro-magnetic switches arranged in local circuits that are controlled by push buttons or the like at a point more or less remote from the main switch.

Still another object of the invention is the provision of a novel arrangement of a main switch, an operating solenoid therefor, and controlling electro-magnetic switches all mounted on a common support.

With such objects in view, and others which will appear as the description proceeds, the invention comprises various novel features of construction and arrangement of parts which will be set forth with particularity in the following description and claims appended hereto.

In the accompanying drawings, which illustrate one embodiment of the invention and wherein similar characters of reference indicate corresponding parts in all the views,

Figure 1 is a front view of the apparatus with portions in section to illustrate the details of construction;

Fig. 2 is a central vertical section of the apparatus; and

Fig. 3 is a diagrammatic view of the various circuit connections.

Referring to the drawing, 1 designates a supporting plate or slab of suitable insulating material which carries the parts of the main switch, the operating solenoid therefor and the controlling switches for the circuits of the windings of the solenoid. In the present instance the main switch is made for a three-wire or three-phase circuit and includes a plurality of contacts 2, 3 and 4, all of the same construction, so that a description of one will suffice for all. Each system of circuit-closing means comprises contact studs 5 and 6, to which respectively the incoming and outgoing wires of the supply and load circuits are connected, and co-operating with these stud contacts is a bridging contact 7 made of laminated springs, which bridging contact is fastened to an arm 8 pivoted on a horizontal axle 9. This axle is journaled in a bracket 10 fastened to the supporting plate or slab 1. Sparking contacts 11 are arranged between the upper contacts 5 and bridging contacts 7 in the usual manner.

Any suitable mechanical means may be employed to move the bridging contacts 7 for the various sets simultaneously. In the present instance a horizontal shaft 12 is mounted in bearings 13 in the forward extremities of the bracket arms 10, and on each shaft is pinned or otherwise secured a toggle arm 14 that is connected by one or more links 15 with its associated contact-carrying arm 8, so that by turning the shaft 12 in one direction or the other the switch is opened or closed. Any suitable means may be provided for preventing short-circuiting between one set of contacts and another, as, for instance, the shaft 12 may be made in sections rigidly connected together by insulation couplings 16. The shaft 12 may be turned by hand to open or close the switch, and for this purpose the centrally-disposed arm 14 has rigidly fastened thereto a handle 17. By swinging the outer end of the handle 17 upwardly the bridging contact 7 will be thrown to circuit-closing position and a reverse downward movement of the handle will effect the opening of the switch.

The main switch is adapted to be opened and closed automatically, and for this purpose a solenoid S is mounted on the panel or supporting plate 1 at a point below the shaft 12. This solenoid has two windings

c and *o*, which are respectively energized to close and open the main switch, and these windings operate on a core 18 which moves vertically and has its upper end provided with a stem or rod 19 that is connected with the hinge joint 20 between the central toggle members 14 and 15. As this hinge 20 swings in an arc of a circle concentric with the shaft 12 the solenoid is mounted to have a sliding movement, and for this purpose the lower extremity of the solenoid body 21 has oppositely-disposed journals or pivots 22 that are carried by bearings 23 on a bracket 24 fastened to the panel 1. Stiffening bars 25 have their lower ends connected with the pivots 22 and their upper ends are rigidly connected at 26 with the central bracket 10. On opposite sides of the main switch solenoid are switch closing and opening control switches C and O which are electrically operated and can be energized from remote points. The opening switch O comprises a casing 27 carried by or fastened to the left side of the bracket 24, and in this casing is a solenoid winding 28 which operates on a core 29 to pull the same downwardly when the winding 28 is energized. This core 29 carries a movable contact 30 adapted to engage fixed contacts 31 and 32 which have binding posts 31^a and 32^a, respectively, for connecting this main switch closing control switch in circuit. A spring 33 operates on the core 29 to raise the same when the winding 28 is deenergized. The closing control switch C for the main switch comprises a casing 34 fastened to the right extremity of the bracket 24, and in this case is a winding 35 operating on a core 36 which carries a movable contact 37 engageable with contacts 38 and 39 which have binding posts 38^a and 39^a for connection with a controlling circuit. The contact 38 is held in open position by gravity acting on it and the core 36, and when the solenoid winding 35 is energized the core is raised to close the circuit that effects the closing of the main switch.

The operation of the apparatus will now be described in connection with the diagram, Fig. 3. *m*', *m*², *m*³ are the service mains which connect with the several stationary contacts 5, and *l*', *l*², *l*³ are the leads for the load circuit and are connected respectively with the contacts 6. Wires 40 and 41 connect the terminals of the closing solenoid winding *c* with the mains *m*', *m*², and in the wire 40 are the contacts 38 and 39 of the closing control switch C, and when the movable contact 37 of such switch engages the contacts 38 and 39 the winding *c* of the main solenoid is energized for the purpose of closing the main switch by moving the core 18 upwardly, which in turn throws the bridging contacts 7 to closed circuit position. The winding 35 of the con-

trolling switch C is connected by wires 42^a and 43^a with a push button 46 from the circuit closing means, and a source of current 45, which may be a local battery, or the line current may be used, the said push button 46 being disposed at any suitable point with respect to the main switch.

The wires 40 and 41 have branches 40^a and 41^a to which the switch opening winding *o* of the solenoid S is connected, and in the wire 40^a are contacts 31 and 32 that are adapted to be engaged by the contact 30 when the winding 28 of the controlling switch O is energized, whereby current will flow through the winding *o* of the solenoid S and thereby operate on the core 18 to open the main switch. The winding 28 of the opening control switch is connected by wires 43 and 42 with an opening push button 44 and the battery 45, the push button 46 being located at the same place with the push button 44, so that from one station the main switch can be either opened or closed. Obviously other opening and closing push buttons can be arranged at other points where they are found desirable. These two push buttons may be incorporated into one device having two buttons, one for closing and the other for opening the circuits.

It is desirable to automatically throw the closing switch C open as soon as the main switch is closed, and for this purpose the core 19 of the solenoid S has a downwardly extending stem 50, which is provided with an adjustable stop 51, and this stop is adapted to engage the inner end 52 of a lever 53, the outer end 54 of the lever being connected with the stem 36^a connected with the core 36 of the closing solenoid. Normally the parts are in the position shown in Fig. 3, and when the solenoid C is energized the core 36 is raised and the lever 53 is tilted so that its inner end will be in engagement with the stop 51. As the core 18 is raised to close the main switch the lever 53 is returned to its original position, and thereby the core 36 is pulled downwardly and the contact 37 disengaged from the contacts 38 and 39, so that the winding *c* of the main solenoid S will be open-circuited. To insure the opening of the opening switch O when the main switch is opened, a lever 55 is connected with the stem 29^a of the core 29, and the inner end 56 of the lever is associated with the stem 50, so that when its inner end 56 is raised during the time the contact 30 of the opening switch is engaged with the contacts 31 and 32, the stop 51 will strike the lever 55 as the main switch opens, so that the opening switch will be thereby automatically opened.

Having thus described my invention, I claim as new and desire to secure by Letters Patent:

1. The combination of a main switch including relatively movable contacts for 13

opening and closing the circuit, a movable carrier for the movable contact, a solenoid including separate windings, a core actuated by the solenoid, a toggle device connected with the carrier and also connected with the core, whereby the latter operates through the toggle device for moving the carrier to and from closed circuit position, secondary electromagnetically operated switches for respectively opening and closing the circuits of the solenoid windings, said secondary switches having movable elements, and interlocking mechanical devices between the movable elements of the secondary switches and the solenoid core, whereby the secondary switches can operate only in a predetermined sequence.

2. The combination of a main switch including fixed and movable contacts, electrical means including separate windings for respectively moving the movable contact to and from closed circuit position, a closing switch for closing the circuit of one winding, an opening switch for closing the circuit of the other winding, said switches being disposed adjacent to the said electrical means, levers connected with the movable elements of the closing and opening switches, and lost motion connection between the levers and the movable element of the said electrical means, whereby the clos-

ing switch is automatically opened after the main switch begins to close and the opening switch is automatically opened after the main switch begins to open.

3. The combination of a main switch having a movable contact element, a solenoid having a core connected with the said element and separate windings operating on the core, a closing switch for closing the circuit of one winding to effect the closing of the main switch, an opening switch for closing the circuit of the other winding to effect the opening of the main switch, the opening and closing switches each having a solenoid including a movable core, levers connected with the said movable cores, and a lost motion connection between the levers and the core of the first-mentioned solenoid, whereby the closing switch is automatically opened after the main switch begins to close, and the opening switch is automatically opened after the main switch begins to open.

In testimony whereof I have signed my name to this specification in the presence of two subscribing witnesses.

CHARLES EMILE PELLETIER.
